UNITED STATES PATENT OFFICE.

HAZEN BOTSFORD BAIRD, OF NEW YORK, N. Y.

HAIR-WAVING APPARATUS.

Application filed July 3, 1926. Serial No. 120,382.

This invention relates to apparatus for use in the treatment of hair to impart to it what is commonly known as a permanent wave. In carrying out that process the strands or the tresses of hair are wrapped about a rod to form a tight curl and these curls are then encased, according to one process, in a piece of cloth or a pad which has been moistened in water containing 5 borax. An outer and protective casing or tube is then placed about the tress so wrapped and a tubular electric heater slipped over the casing or tube and the tress heated by the current for a sufficient period 10 of time to cause the hair to assume the permanent curl.

In an average permanent waving operation, the head of hair is divided into a large number of tresses, as for example, 36 or 40, 20 and in carrying out the process, the tresses are all wound on rods one after another and the heating operation for all of the 25 curls carried on simultaneously. This necessitates the use of apparatus which includes a large number of electric heaters with their current connections and control devices, and means for supporting these heaters so that their weight will not be assumed by the person undergoing the treatment. In view of 30 the large number of heaters necessary, each of which has its adjustable mounting, the apparatus which has heretofore been used for permanent waving has been clumsy and complicated and such apparatus can only be moved about with difficulty. As the preparation of the curls is a long and tedious 35 process, while the heating only consumes a short time, a single machine, if portable, could be used for giving several treatments, 40 the preparation for which had been carried on simultaneously. Also, such a portable machine would permit the treatment to be given at home, or the operator could take the machine from shop to shop.

45 The apparatus heretofore provided for the purpose, however, has not been capable of such use on account of its large size and weight and also on account of the large number of cords or wires which would 50 quickly become tangled if any attempt were made to take the apparatus down.

55 The object of the present invention, accordingly, is to provide a portable apparatus for use in permanent waving which is simple in construction and light in weight. This apparatus is constructed primarily to

permit of its ready assembly and disassembly and it is so arranged that the individual heaters with their current carrying wires may be separately removed from the apparatus, and parts of the latter which provide a support for the heaters may then be folded to make the apparatus more compact. Also, the apparatus includes improved adjustment devices by which the position of the heaters 60 may be varied as desired, thus insuring that the combination will not have to bear the weight of any single heater. These adjustment devices are readily removable with the heaters and their conductors and when 65 the apparatus is demounted, it may readily be transported in two small boxes. The invention also includes an improved type of heater in which the heating element is protected against moisture and the supply wires 70 against short circuiting due to chafing of their insulation.

75 One form of the new apparatus which has been found to be satisfactory, includes a casing of metal suitably finished and preferably in the form of a flat drum having a vertical peripheral side wall. Extending outwardly from the side wall are arms, pivotally secured to the casing, and held in any position of adjustment from horizontal 80 to vertical with reference to the casing, by suitable adjustment means. In the wall of the casing are mounted separable plugs arranged in a series extending completely 85 around the casing and supplied with current by two cables so arranged that there are two circuits, each of which contains half of the plugs. The end of each plug has a separable portion, which is connected to the 90 ends of a pair of double cables, each of which supplies a heater.

95 These heaters are arranged in two concentric series below the casing, and the heaters of the inner series are supported by 100 adjustment devices suspended from the casing itself, while each heater of the outer series is carried by an adjustment device mounted on the end of one of the arms. These adjustment devices permit the positions of the heaters, with reference to the 105 casing, to be varied as desired, and are arranged to permit a fine adjustment so that the weight of each heater and its wires is entirely carried by the apparatus and is not borne by the person whose hair is being 110 treated. With this arrangement of the heaters in two concentric series, the heaters

are most conveniently placed and their adjustment may be readily carried on, without tangling their supply wires.

The casing is suspended from an arm, 5 which may be secured to a standard mounted on a base provided with rollers or may be mounted in a bracket permanently secured to a wall or other fixed support. When the apparatus is to be transferred, the adjustment devices carrying the cables are disconnected from the casing and the arms, and separable portions of the plugs are removed, and the wires, with the heaters attached, 10 folded in any convenient manner. The casing is then removed from the supporting arm and the casing arms are raised to vertical position, thus greatly reducing the dimensions of the casing and permitting its transportation in a relatively small box. 15 The supporting arm for the casing and the wires with the heaters attached may then be placed in another box of small compass and when the apparatus is to be set up the parts are assembled readily and without difficulty as indicated.

For a better understanding of the invention, reference will be made to the accompanying drawings in which:

Fig. 1 shows a side view of the apparatus 30 with certain parts removed.

Fig. 2 is a top plan view of the apparatus with various parts removed and certain parts broken away.

Fig. 3 is a fragmentary vertical sectional view showing the mounting of one of the 35 radial arms.

Fig. 4 is a fragmentary view in side elevation showing an adjustment device for the arms, and

Fig. 5 is a longitudinal sectional view 40 through my improved heater.

Referring now to the drawings, the apparatus is shown as including a casing 10 of circular cross section and having a continuous vertical peripheral side wall 11. The casing is closed top and bottom by suitable plates, and a rod 12 passing through both top and bottom walls carries a head 13 by its lower end on which the 45 casing rests. The rod 12 is fitted into a ring 14, which may be mounted on a supporting arm 15 being slideable thereon to any desired position and secured in that position by a thumb-screw 16. The rod 15 is preferably a piece of pipe which may be threaded into an elbow 17 mounted on the end of a vertical length of pipe 18 supported adjustably in brackets 19 extending from a plate 20 secured to a wall. If desired the 50 rod 18 may extend downwardly to the base mounted on rollers.

From the lower outer edge of the peripheral wall of the casing extend a plurality of arms 21, these arms being pivotally mounted 65 at 22 and foldable to the outlined position

indicated in dotted lines at 23. In the standard machine there will be 18 such arms and at its outer end each arm carries a spring take-up device 24 having a hook 25 which may be inserted in a ring 26 at the end of 70 the arm. These spring take-up devices include a metal tape 27 which is wrapped about a drum, the construction being similar to that commonly employed in spring take-up devices used with eyeglass chains. 75 These take-up devices are of standard commercial construction and need not be further described. They provide a means for supporting the heaters 28 with reference to 80 the casing.

In the standard machine there are thirty-six heaters although a greater or less number may be provided as desired. These heaters are arranged in two concentric series, eighteen in a series and each heater of 85 the outer series is carried by means of a ring 29 and hook 30 by the take-up tapes 27. Each heater is supplied with current through connecting wires 31 leading to a plug 32 in the casing, while each such plug 90 is connected by wires 31 to a heater of the inner series and a heater of the outer series, and the heaters of the inner series are suspended from take-up devices 33 which hang 95 from rings 34 mounted in the bottom of the casing near its side wall. With this arrangement it will be seen that each terminal plug supplies current to a heater of each series and each heater has its associated 100 take-up device, the heaters of the outer series being supported by take-up devices carried by arms, while the heaters of the inner series are supported by take-up devices suspended from the casing. These take-up devices support the weight of the heaters and 105 their supply wires and permit the position of the heaters to be exactly adjusted with reference to casing.

The plugs 32 are of a suitable type, with the supply wires 31 connected to the removable portions 35. The fixed portions 36 are mounted fixedly in the casing wall and are supplied with current from a cable 37 which is connected to any convenient source of power and leads into the interior of the 115 casing through the upper wall thereof and supplies current to mains 38 and 39. The mains 38 supply current to nine of the plugs while the mains 39 supply current to the remainder. Thus, the heaters are supplied with current in two groups and in the circuit for each group is connected a pilot lamp 40 the plugs and the lamps being connected across the mains in parallel.

My improved heater illustrated in Fig. 5 125 comprises an inner metal tube 41 which is partially enclosed by an outer tube 42. At one end 43 the outer tube is turned inwardly to bear against the outer wall of the inner tube and where contact is made the tubes 130

are secured together in a water-tight manner, preferably by welding. In the spaces between the tubes is a heating element 44 of standard type enclosed in insulation and the 5 supply wires 45 for this element pass through an aperture in a plate 46 which is slipped over one end of the inner tube and bears against the end of the outer tube. The 10 end of the inner tube opposite to that on which the outer tube is mounted carries a handle 47 which may be made of heat insulating material, such as cork, and the portion 15 of the inner tube which lies between the handle and the plate 46 is enclosed in a heat insulating wrapping 48 of asbestos cord, for example. This cord is likewise wrapped about the wires 45 as at 49 for a substantial distance, thus holding the wires together and preventing their chafing at the point 20 where they pass through the plate 46 and beyond. Also secured to the wires is a ring 50 by which the heater may be suspended from one of the take-up devices. With this 25 heater it will be observed that the heating element is fully protected and moisture cannot enter the space between the tubular members. Likewise, the wires leading to the 30 heating element are kept from chafing, which would result in their becoming short circuited.

In the construction shown in Figs. 1 and 3 the arms 21 are supported when in their horizontal position by means of bead chains 51, each arm having its individual chain secured thereto midway of the arm and also secured to the casing at any convenient point. Instead of this construction that illustrated in Fig. 4 may be used in which each arm 21 is pivotally attached to a curved rod 52 having teeth 53 in its lower edge. This rod enters an aperture or slot in the casing wall and the arm 21 may be held in any position of adjustment by swinging the arm so that rod 52 enters the casing. In 45 each position of adjustment the teeth 53 will engage the casing wall and hold the rod at the desired angle.

It will be seen that this apparatus, which is made of light metal, is particularly adapted for ready assembly and disassembly. When the apparatus is to be transported the separable portions 35 of the terminal plugs are removed from the casing wall and the connecting wires disengaged from the take-up devices. The latter may then be removed 55 from the arms 21 and the casing.

The cap 54 on the end of the arm 15 is now removed and the supporting ring 14 for the casing slipped off the end of the arm 15. The arms 23 are now swung to vertical position and the casing may be placed in a box of small compass. The arm 15 is now unscrewed from the elbow 17 and the elbow 60 and the rod 18 to which it is secured are then removed from the brackets 19. The

arm and its supporting rod together with the heaters and their wires and take-up devices may be placed in another box of small dimensions and the complete apparatus may thus be carried from place to place. When 70 the apparatus is to be set up the parts are to be assembled in a manner which will be readily understood from the foregoing. The apparatus is relatively light in weight and owing to the manner in which the connections to the heaters are made, the manipulation of the device and its assembly and disassembly requires only a short time. These 75 spring take-up devices are relatively noiseless so that the position of the heaters may 80 be readily adjusted without causing either discomfort or frightening the person whose hair is being treated.

I claim:

1. Apparatus for treating hair comprising 85 the combination of a support, a casing carried thereby, a plurality of arms extending outwardly from the casing, a plurality of heaters arranged in an inner and an outer series, and individual devices for adjusting 90 the positions of the heaters with reference to the casing, the devices for the heaters of the outer series being carried by the said arms and the devices for the heaters of the inner series being carried by the casing. 95

2. Apparatus for treating hair comprising 100 the combination of a support, a casing carried thereby, a plurality of arms extending outwardly from the casing, a plurality of heaters arranged in an inner and an outer series, individual devices for adjusting the 105 positions of the heaters with reference to the casing, the devices for the heaters of the outer series being carried by the said arms and the devices for the heaters of the inner series being carried by the casing, terminal 110 plugs in the wall of the casing, and connections from the plugs to the heaters.

3. Apparatus for treating hair comprising 115 the combination of a support, a casing carried thereby, a plurality of arms extending outwardly from the casing, a plurality of heaters arranged in an inner and an outer series, individual devices for adjusting the 120 positions of the heaters with reference to the casing, the devices for the heaters of the outer series being carried by the said arms and the devices for the heaters of the inner series being carried by the casing, terminal plugs mounted in the wall of the casing, and connections from the plugs to the heaters each plug being connected to a heater of each series. 125

4. Apparatus for treating hair comprising 130 the combination of a support, a casing carried by the support and having a continuous peripheral wall, a plurality of arms pivotally mounted on the casing and extending outwardly from the said wall, these arms being capable of being moved to a posi-

tion parallel to the said wall, a plurality of heaters arranged in an inner and an outer concentric series and individual devices for supporting the heaters and permitting their adjustment with reference to the casing, the devices for the heaters of the outer series being carried by the said arms and the devices for the heaters of the inner series being carried by the casing.

5. Apparatus for treating hair comprising the combination of a support, a casing carried by the support and having a continuous peripheral wall, a plurality of arms pivotally mounted on the casing and extending outwardly from the said wall, these arms being capable of being moved to a position parallel to the said wall, a plurality of heaters arranged in an inner and an outer concentric series, individual devices for supporting the heaters and permitting their adjustment with reference to the casing, the devices for the heaters of the outer series being carried by the said arms and the devices for the heaters of the inner series being carried by the casing, terminal plugs mounted in the peripheral wall of the casing between the arms and connections between each plug and a pair of heaters.

6. Apparatus for treating hair comprising the combination of a support, a casing carried thereby, a plurality of arms extending outwardly from the casing, a plurality of heaters arranged in an inner and an outer series, individual devices for adjusting the positions of the heaters with reference to the casing, the devices for the heaters of the outer series being carried by the said arms and the devices for the heaters of the inner series being carried by the casing, a plurality of separable plugs each having a portion mounted fixedly in a wall of the casing and another portion removably secured to the first portion and connections between each of the said removable portions and a pair of heaters.

7. Apparatus for treating hair comprising the combination of a support, a casing carried thereby, a plurality of arms extending outwardly from the casing, a plurality of heaters arranged in an inner and an outer series, terminal plugs in the wall of the casing, a connection from each heater to one of the plugs, and spring take-up devices secured to the connections, the heaters of the outer series being supported by take-up devices mounted on the arms and the heaters of the inner series being supported by devices secured to the casing.

8. Apparatus for treating hair comprising the combination of a support, a casing carried thereby, a plurality of arms extending outwardly from the casing, a plurality of heaters arranged in an inner series suspended from the casing and an outer series, each heater of the outer series being suspended

from one of the arms, terminal plugs in the wall of the casing, connections between the plugs and the heaters, main terminal plugs mounted in the casing and a cable within the casing connected to the main terminal and also connected to a plurality of the terminal plugs.

9. Apparatus for treating hair comprising the combination of a support, a casing carried thereby, a plurality of arms extending outwardly from the casing, a plurality of heaters arranged in an inner series suspended from the casing and an outer series, each heater of the outer series being suspended from one of the arms, terminal plugs in the wall of the casing, connections between the plugs and the heaters, main terminal plugs mounted in the casing, connections between the plugs and the heaters, a supply cable within the casing for supplying current to a plurality of plugs and a pilot lamp connected in parallel with the plugs.

10. Apparatus for treating hair comprising the combination of a support, a casing carried thereby, a plurality of arms extending outwardly from the casing, a plurality of heaters arranged in an inner series suspended from the casing and an outer series, each heater of the outer series being suspended from one of the arms, terminal plugs in the wall of the casing, connections between the plugs and the heaters, main terminal plugs mounted in the casing, connections between the plugs and the heaters and cables within the casing connected to the plugs and supplying the heaters with energy in two circuits, and a pilot lamp in each circuit.

11. A portable apparatus for treating hair, comprising the combination of a demountable support, a casing removably connected thereto, a plurality of arms extending outwardly from the casing, a plurality of heaters arranged in an inner and an outer series, a plurality of terminal plugs each having a portion fixedly mounted in the casing wall and another portion removably secured to the first portion, connections between the removable plug portions and the heaters, and individual devices detachably secured to the arms and the casing for adjusting the position of each heater with reference to the casing, the devices secured to the arms carrying the heaters of the outer series and the devices secured to the casing carrying the heaters of the inner series.

12. Apparatus for treating hair comprising the combination of a support, a casing carried thereby, a plurality of arms extending outwardly from the casing, a plurality of heaters arranged in an inner and an outer series, individual devices for adjusting the positions of the heaters with reference to the casing, the devices for the heaters of the outer series being carried by the said arms and the devices for the heaters of the inner

series being carried by the casing, and means connected to the arms and engaging the casing for holding the arms in even position of adjustment relative thereto.

5 13. In apparatus for treating hair a heater comprising an inner tubular member adapted to receive a curl of hair, an outer tubular member enclosing a portion of the inner member and having one end edge turned inward toward the outer wall of the inner member and secured thereto with a watertight connection, a heating element in the

space between the tubular members, supply wires for the element leading from the space, a heat insulating handle mounted on the end of the inner member adjacent the free end of the outer member and a protective wrapping of heat insulating material applied to the inner member between the handle and the free end of the outer member, this wrapping also enclosing both wires for a substantial distance. 15 20

In testimony whereof I affix my signature.
